UNITED STATES PATENT OFFICE

2,099,373

MINING APPARATUS

Dwight R. Richards, Claremont, N. H., assignor
to Sullivan Machinery Company, a corporation
of Massachusetts

Application April 26, 1934, Serial No. 722,568

48 Claims. (Cl. 262—28)

This invention relates to mining apparatus, and more particularly to improvements in coal mining apparatus of the combined horizontal and shear cutter, wheel mounted type, adapted 5 to operate from the mine trackway.

An object of this invention is to provide an improved coal mining apparatus. Another object is to provide an improved coal mining apparatus of the combined horizontal and shear cutter type having an improved adjustable supporting structure for the kerf cutting mechanism whereby the kerf cutter may be positioned through a relatively wide cutting range. Yet another object is 10 to provide an improved adjustable supporting structure for the kerf cutting mechanism, having a relatively great universality whereby the kerf cutter may be positioned to cut kerfs in any desired location in the coal face and ribs, thereby suit practically any mining conditions encountered. A further object is to provide an improved supporting and adjusting structure whereby the kerf cutter may be supported and adjusted in an improved manner, and wherein an improved 15 swinging arm structure is provided for supporting the kerf cutter, and having adjustment horizontally and vertically, thereby to position the kerf cutter to cut horizontal kerfs at any desired location between the mine floor and mine roof, and to cut vertical kerfs at any desired location 20 between the ribs and in the ribs. Yet another object is to provide an improved mining apparatus of the wheel mounted, track supported and guided type having improved adjustable kerf cutting mechanism whereby kerfs may be cut at 25 or near the level of the mine floor outside and below the level of the mine trackway, in any desired horizontal plane between the mine roof and the mine floor, and in vertical planes. Still another object is to provide an improved coal 30 mining apparatus having improved kerf cutter supporting and adjusting means of a truly universal character whereby an extremely wide range of adjustment of the kerf cutter is possible. Still another object is to provide, in a mining 35 apparatus of the above character, improved adjusting and swinging mechanism for the kerf cutter and improved mechanism for propelling the apparatus. These and other objects and advantages of the invention will, however, hereinafter 40 more fully appear in the course of the following description and as more particularly pointed out in the appended claims.

In the accompanying drawings there is shown, for purposes of illustration, one form which the 45 invention may assume in practice.

In these drawings,—

Fig. 1 is a plan view of the illustrative form of the improved mining apparatus.

Fig. 2 is a side elevational view of the mining apparatus shown in Fig. 1, with the cutting 5 mechanism shown in transport position, as indicated in full lines.

Fig. 3 is a central, longitudinally extending, vertical sectional view taken substantially on line 3—3 of Fig. 1.

Fig. 4 is a longitudinally extending vertical sectional view taken substantially on line 4—4 of Fig. 1.

Fig. 5 is a detail sectional view taken on line 5—5 of Fig. 4.

Fig. 6 is a horizontal sectional view taken substantially on line 6—6 of Fig. 7.

Fig. 7 is a longitudinally extending, vertical sectional view taken substantially on line 7—7 of Fig. 1.

Fig. 8 is a detail sectional view taken on line 8—8 of Fig. 7.

Fig. 9 is a cross sectional view taken on line 9—9 of Fig. 7.

Fig. 10 is a detail horizontal sectional view 25 taken on line 10—10 of Fig. 7.

Fig. 11 is a cross sectional view taken on line 11—11 of Fig. 4.

Fig. 12 is a cross sectional view taken on line 12—12 of Fig. 4.

Fig. 13 is a fragmentary side elevational view, with parts shown in vertical section, showing a portion of the arm swinging mechanism.

Fig. 14 is an enlarged horizontal sectional view showing details of the propelling mechanism.

Fig. 15 is a cross sectional view taken on line 15—15 of Fig. 14.

Fig. 16 is a cross sectional view taken on line 16—16 of Fig. 14.

Fig. 17 is a horizontal sectional view, with parts shown in plan, illustrating the cutter swinging mechanism, the view being taken substantially on line 17—17 of Fig. 3.

Fig. 18 is a detail view showing a portion of the mechanism of Fig. 17.

Fig. 19 is a diagrammatic view showing the improved hydraulic control means for the various hydraulically operated devices.

In this illustrative embodiment of the invention, there is shown a coal mining apparatus of the combined horizontal and shear cutter, wheel mounted type adapted to operate while supported and guided by a mine trackway, commonly known as a "coal saw" of the track type, and generally comprising a self-propelled portable base 1, 50

a horizontally swingable frame structure 2, a vertically swingable arm structure, generally designated 3, a revolving support 4, and a swingable cutter support 5. The portable base is herein in the form of a low compact truck frame 6 mounted on truck wheels 7 adapted to run along a mine trackway 8 laid on the mine floor. The swingable frame 2 is in the form of a horizontal turntable 9 having a projecting horizontal arm 10 overlying the forward end of the base and supporting at its outer extremity a depending frame portion 11 on which the arm structure 3 is pivotally mounted on a horizontal axis at 12 for swinging movement in a vertical direction relative to the frame 2. The revolving support 4, which might be termed a rotatable cutter head, projects forwardly from the outer extremity of the arm structure 3 to form an elongation of the latter, and is rotatable about the longitudinal axis of the arm structure on an axial line extending radially with respect to the arm pivot axis 12. The cutter support 5 is swingably mounted at 13 about an axis arranged at right angles with respect to the axis of rotation of the support 4, and pivotally mounted at 14 about an axis at right angles with respect to the cutter support axis 13 is an elongated plane kerf cutter 15. Improved devices are provided for swinging the frame 2 with respect to the truck, for swinging the arm structure, for revolving the "cutter head" support 4 with respect to the arm structure, and for swinging the cutter support 5 with respect to the rotatable support, and improved motor operated devices are also provided for propelling the apparatus and for actuating the cutting elements of the kerf cutter, as will hereinafter be described.

The turntable 9 is mounted on the base 1 directly above the truck wheel axes in a position overlying the wheel base, and is guided for horizontal swinging movement with respect to the base by an annular bearing flange 17 extending about the periphery of the circular turntable casting 18, and this bearing flange is guided in an arcuate guideway 19 formed by means of a segmental plate 20 secured by screws 21 to the top of the truck frame 6. The turntable casting 18 is also provided with a circular frame portion 22 journaled in a bearing sleeve 23 supported within a circular projection 24 formed integral with the truck frame. The arm-like portion 10 of the turntable casting, as above mentioned, overlies the base frame, and the depending frame portion 11 overhangs the forward end of the base; and this arm portion is guided, on horizontal swinging movement of the turntable casting relative to the base, by means of an arcuate guide flange 25 formed integral with the truck frame and with which an underlying lip 26 formed on a guide block 27 engages. The block 27 is secured between depending side flanges formed on the bottom portion of the arm 10, and is secured in position on the arm by bolts 28. The flange 25 is also provided with an upstanding projection engaging an arcuate bearing portion 29 formed on an arcuate projection 30 integral with the bottom portion of the arm 10.

The arm structure 3 has formed thereon lateral trunnion arms 32, 32 having trunnion portions 33 journaled on alined shafts 34 supported within lugs 35 formed integral with the depending frame portion 11, and the rearward portion of this arm structure is provided with a spherical housing 36 projecting in a chamber 37 formed within the depending frame 11 and mounted to revolve

therein. Secured to the frame 11 is an annular plate 38 carrying a sealing ring 39 for sealing the housing from the exterior while permitting the spherical portion 36 to revolve therein. The outer extremity of the arm structure 3 has supported therein a bearing sleeve 40 within which is rotatably mounted the rearward portion of the revolving "cutter head" support 4. The support 4 is provided with an elongated tubular body 41 secured, as by welding or otherwise, at 42, on a circular projection integral with a rotatable supporting frame 43; and the forward extremity of the tubular portion 41 is, as shown in Figs. 6 and 7, secured, as by welding or otherwise, at 44, to a cylindrical portion of a front support 45, 15 the latter forming the forward extremity of the revolving "cutter head" support and the outer extremity of the arm structure on which the cutter support 5 is swingably mounted.

Now referring to the improved cutter driving means, it will be noted that mounted on the rearward portion of the truck frame at the rear of the turntable 9 and supported independently of the latter, is a motor 47 which constitutes the sole prime mover for the various mechanisms and devices of the apparatus. This motor is herein preferably of the reversible electric type, having a suitable electrical controlling and reversing apparatus 48. The power shaft 49 of this motor is herein horizontally disposed and extends longitudinally of the apparatus, and is secured by a suitable coupling 50 to an alined transmission shaft 51, herein suitably journaled within the truck frame 6. In this instance, keyed to the forward end of the shaft 51 is a bevel gear 52 meshing with a bevel gear 53 journaled on suitable bearings supported by a vertical shaft 54, herein arranged with its axis coinciding with the turntable axis and supported at its lower end at 55 within the bottom bearing portion of the truck frame. Formed integral with and rotatable with the bevel gear 53 is a bevel gear 56 meshing with a bevel gear 57 keyed to the rear end of a horizontal transmission shaft 58. As shown in Fig. 3, this transmission shaft is suitably journaled in the swinging turntable frame 2 and projects at its forward end within the chamber 37. Keyed to this projecting end of the shaft 58 is a bevel gear 59 meshing, as shown in Fig. 5, with a bevel gear 60 keyed to a horizontal shaft 61 suitably journaled within the spherical frame portion 36 of the swinging arm structure 3. This bevel gear 60 meshes with a bevel gear 62 keyed to the rear end of a transmission shaft 63, herein journaled within the frame 64 of the arm structure 3 and arranged with its axis extending at right angles to the axis of the horizontal shaft 61. This shaft 63 has alined therewith a transmission shaft 65 suitably journaled within the revolving support 4, and the shaft 65 is connectible in driving relation with the shaft 63 by a sliding clutch member 66 having clutch teeth interlocking with teeth on the shaft 65 and engageable with clutch teeth 67 formed on the forward end of the shaft 63. This clutch member 66 is provided with a clutch shipper 68 having a suitable operating handle 69 conveniently arranged exteriorly of the arm structure, as shown in Fig. 1.

As shown in Figs. 6 and 7, the forward end of the transmission shaft 65 has keyed thereto a bevel gear 70 meshing with a bevel gear 71 journaled on suitable bearings supported by a stub shaft 72 arranged with its axis angularly disposed with respect to the axis of shaft 65 and 75

preferably midway between the axis of the shaft 65 and the pivotal axis 13 of the swingable cutter support 5. This bevel gear 71 meshes with a bevel gear 73 keyed to a shaft 74 suitably journaled within bearings supported by the front support 45 of the revolving support and the frame 75 of the swingable cutter support 5. This shaft 74 is herein arranged with its axis alined with the pivotal axis 13 of the swingable cutter support 5, and has keyed thereto and rotatable therewith a bevel gear 76 meshing with a bevel gear 77 keyed to a shaft 78, herein journaled within the swingable cutter support frame 75 and arranged with its axis coinciding with the bar pivot axis 14. Secured to the shaft 78 and driven thereby is a chain sprocket 79 which engages and drives an endless cutter bit carrying cutter chain 80 mounted on the margin of an elongated, extremely thin, plane cutter bar 81 for circulation thereabout, the cutter chain and cutter bar forming the component elements of the kerf cutter 15.

As mentioned above, the kerf cutter 15 is mounted for pivotal movement with respect to the swingable cutter support 5, and the mounting means for the kerf cutter herein comprises a hanger frame 82 having a circular bearing portion 83 rotatably mounted on bearing sleeves 84 supported by a central circular portion 85 of the cutter support frame 75. As shown, this circular portion 85 surrounds the shaft 78 and provides supporting means for the bearings of this shaft. Integral with the circular bearing portion 83 of the hanger frame is a circumferential flange 86, and this flange is provided with a plurality of radially located notches 87 spaced circumferentially about its peripheral edge and with which there is engageable a rotatable locking pin 88 rotatably mounted in a bearing sleeve 89 supported by the cutter support frame 75. This pin is provided with suitable turning means, and a transverse slot 90 is cut in its body so that when the pin 88 is rotated into its released position, the hanger frame 82 is free to swing with respect to the cutter support frame 75. To provide tightening means for the cutter chain, the cutter bar 81 is formed, as shown in Fig. 9, with lateral guides 92 receivable in guideways 93 formed on the hanger frame 82, so that the cutter bar may slide radially endwise with respect to the chain sprocket axis, and the means for adjusting the bar comprises a bolt 95 having a T-shaped head 96 seated with a complementary socket 97 formed in the adjacent face of the hanger frame 82 and held within the socket by the adjacent surface of the bar 81, in the manner shown in Fig. 7. Threadedly engaged with this bolt is a rotatable nut 98 journaled in a support 99 formed on the bar, and this nut is held against axial movement with respect to this support so that when the nut is rotated the latter moves axially with respect to the bolt, thereby to move the cutter bar 81 relative to its guideways on the hanger frame.

Cooperating with the annular bearing member 83 and bearing sleeve 84 in guiding the cutter bar during swinging of the latter, there is formed on the cutter support frame 75 an arcuate flange 100, held in a guideway 101 on the hanger support by a segmental plate 102 secured to the hanger support by screws; the elements 100, 101, 102 cooperating to form an arcuate guide on a radius struck from the cutter bar pivot axis 14. It will thus be seen that the kerf cutter may be locked in different predetermined angular positions with respect to the cutter support and may be entirely released

for free swinging movement with respect to the cutter support.

Now referring to the improved mechanism for rotating the revolving "cutter head" support 4 relative to the arm structure 3 and for swinging the cutter support 5 with respect to the revolving support, it will be noted that keyed to the transmission shaft 63 of the arm structure is a spur gear 103 meshing with a spur gear 104 journaled, as shown in Fig. 4, on a transmission shaft 105, the latter in turn being journaled within the arm structure 3 and arranged parallel with the shaft 63. Also keyed to the shaft 63 is a spur gear 108 meshing, as shown in Fig. 11, with an intermediate gear 107, in turn meshing with a spur gear 103 arranged coaxial with the gear 104 and similarly journaled on the shaft 105. It will thus be seen that the gear elements 104 and 108 constitute the terminal elements of a reversing mechanism for rotating the shaft 105 in either of opposite directions; and these terminal elements are selectively connectible in driving relation with the shaft 105 by multiple disc clutches 109 and 110, respectively. These clutches have suitable operating means 111 mounted on the shaft 105 between the terminal gear elements and provided with suitable ball bearing pressure plates 112, 113 for the disc clutches respectively. This shipper member is provided with a shipper yoke 114 having a suitable operating handle 115 conveniently arranged on the exterior of the arm frame, as shown in Fig. 1.

Splined to the forward extremity of the shaft 105 is a clutch member 116 having clutch teeth 117 formed on the adjacent face of a spur gear 118. The clutch member 116 is provided with a shipper yoke 119 having a suitable operating lever 120 conveniently arranged on the exterior of the arm frame, as shown in Fig. 1. The spur gear 118 is journaled on the shaft 105 and meshes with a spur gear 121 keyed to the rear end of a tubular transmission shaft 122. The shaft 122 is arranged with its axis alined with, and surrounds, the transmission shaft 65, and is similarly journaled within the revolving "cutter head" support 4. As shown in Figs. 6 and 7, keyed to the forward end of this tubular shaft 122 is a spur gear 123 meshing with a spur gear 124 keyed to the rear end of a screw shaft 125. This screw shaft is arranged parallel with the transmission shaft 65 and is suitably journaled on the side of the revolving support 4, and threadedly engaging this screw shaft is a sliding nut 126 guided in a guideway 127 extending longitudinally of the revolving support. The nut 126 is in the form of a sliding trunnion block, and, as shown in Fig. 8, pivotally connected to trunnion pins 128 formed integral with the nut are links 129, 129, in turn pivotally connected at their forward ends at 130 within projecting lugs 131 formed integral with the swingable cutter support 5. As shown in Figs. 6 and 7, the frame 75 of the swingable cutter support is provided with trunnions 132, 132 journaled in bearing sleeves 133 supported within trunnion supports 134, herein formed integral with the support 45 at the forward end of the revolving support 4, these trunnions forming a pivotal mounting for the cutter supports, whereby the latter may be swung with respect to the revolving support on the pivotal axis 13. It will thus be seen that, depending upon which of the disc clutches 109, 109 is applied, and when the clutch 116 is connected, the cutter support 5 may be swung in one direction or the other on its pivotal axis 13 by the screw, nut and link mechanism 125, 75

- 126, 129. The threads of the screw 125 are self-locking so that when the swinging mechanism is released from its drive the cutter support is locked in its adjusted position.
- 5 125. The mechanism for rotating the revolving "cutter head" support 4 about its longitudinal axis with respect to the swinging arm structure 3 herein comprises a spur gear 136 journaled on the shaft 105 and connectible to the shaft by clutch 10 teeth on the clutch member 116 engageable with clutch teeth 137 on the gear 136. The gear 136 meshes with a spur gear 138 journaled on the bearing sleeve 48 on which the revolving support 4 is journaled. As shown most clearly in Figs. 4 and 12, the hub of the gear 138 is formed with an eccentric portion 139 on which is journaled, on roller bearings 140, a drive ring 141. Secured by bolts 142 to the frame of the arm structure 3 is a guide ring 143 having a series of radially 20 located chambers 144 in which are guided radial plungers 145. The ring 141 engages, in sliding abutting relation, with the inner ends of the plungers 145, and the outer ends of these plungers are provided with tooth-shaped portions engageable with teeth 146 formed on a ring 147 secured to the revolving support 4. The frame 147 is journaled in the bearing sleeve 148 supported in a circular frame portion 149 formed integral with the arm structure frame. This cam and plunger mechanism forms what may be termed a "helio-centric" or continuous wedge speed reducing mechanism. Thus it will be seen that when the gear 136 is connected by the clutch 116 in driving relation with the shaft 63 and one or the other 30 of the disc clutches 108, 109 is applied, the revolving support 4 may be rotated with respect to the arm structure through the gearing 136, 138 and the eccentric and sliding plunger mechanism 139, 145 and 146.
- 40 40. The mechanism for swinging the turntable frame horizontally relative to the base and for swinging the arm structure 3 vertically with respect to the swinging frame will now be described. Referring first to the arm swinging mechanism, it will be noted that pivotally connected at 150 to the opposite sides of the depending frame portion 11 of the swinging frame, and arranged at opposite sides of the arm structure, are vertically swingable cylinders 151 having reciprocable therein pistons 152. These pistons have upwardly projecting piston rods 153 each passing through a stuffing box 154 carried within the head 155 of each of the cylinders, and these piston rods are pivotally connected at their 50 outer extremities, at 156, within projections 157 formed integral with the arm structure frame. It will thus be seen that when liquid under pressure is supplied to one end or the other of the cylinders, the pistons are reciprocated either outwardly or inwardly, thereby to effect swinging of the arm structure 3 either upwardly or downwardly on its pivotal axis 12. By suitably controlling the liquid within the ends of the cylinders, the pistons may be locked in any desired position, thereby to maintain the arm structure in any 60 desired position of adjustment.
- 70 70. The improved mechanism for swinging the turntable frame 2 horizontally with respect to the base comprises, as shown in Fig. 17, horizontal swingable cylinders 158 and 159 each pivotally connected at one end, at 160, to a pin 161 suitably supported within the frame 2. Reciprocable within each of the cylinders is a piston 162 having a piston rod 163 passing through a suitable 70 stuffing box 164 carried by the cylinder head 165. One piston rod is pivotally connected at 166 to a pin 167 supported within an arcuate frame 168, while the other piston rod is connected by a similar pin 169 to the opposite end of the arcuate frame 168. The top and bottom surfaces of this 5 arcuate frame are guided within bearing elements 170 and 171 within arcuate guideways 172 and 173 formed in the top portion of the truck frame 6 and an upper detachable plate 175 forming a portion of the turntable frame. This arcuate guide frame is movable in an arcuate path struck from the axis of the turntable, and carries a plurality of, herein three, pinions 176 journaled on vertical studs 177 supported, as shown in Fig. 3, within the arcuate frame 168. These pinions mesh with the teeth of an arcuate rack 178 formed on a segmental plate 179 secured, as by screws, to the top of the truck frame. The inner sides of these pinions 176 also mesh with the teeth of an arcuate rack 180 formed on a segmental 10 frame portion 181 of the turntable casting. The pitch circles of the teeth of the arcuate racks 178, 180 are struck from the axial center of the turntable.
- 15 25 30 35 40 45 50 55 60 65 70 75 80 85 90 95 100 105 110 115 120 125 130 135 140 145 150 155 160 165 170 175 180 185 190 195 198 199 200
- When liquid under pressure is supplied to the cylinders 158, 159 at one side of one piston and at the opposite side of the other, the arcuate frame 168 is moved arcuately within its guideways, moving the pinions 176 therewith. The teeth of these pinions reacting on the teeth of the arcuate rack 178 cause the pinions to rotate, thereby effecting arcuate movement of the rack 180, turning therewith the turntable frame and swinging the latter about its axis with respect to the base. When liquid under pressure is supplied to the opposite sides of the pistons, the parts are of course moved in the opposite direction, thereby swinging the turntable frame in the opposite direction. Upon trapping liquid in the cylinders at opposite sides of the pistons, the pistons may be locked, thereby to hold the turntable in its adjusted position. The liquid supply and controlling connections for the turntable rotating and arm swinging cylinders will later be described.
- 45 50 55 60 65 70 75 80 85 90 95 100 105 110 115 120 125 130 135 140 145 150 155 160 165 170 175 180 185 190 195 198 199 200
- Now referring to the propelling mechanism for the apparatus, it will be noted that keyed to the shaft 51, as shown in Fig. 3, are spur gears 185, 186, and as shown in Fig. 14 the gear 186 meshes with a spur gear 187 suitably journaled on a tubular shaft 188, herein suitably journaled within the truck frame. The gear 185 meshes, as shown in Fig. 15, with an intermediate gear 189, in turn meshing with a spur gear 190 arranged coaxial with the spur gear 187 and similarly journaled on the tubular shaft 188. The gears 187, 190 constitute the terminal elements of a reversing mechanism for effecting drive of the tubular shaft 188 in either of opposite directions, and these terminal elements are selectively connectible to the shaft 188 by multiple disc clutches 191, 192. These clutches are provided with suitable operating mechanism including a ball bearing operating member 193 surrounding the shaft 188 between the gears 187, 190 and having a suitable shipper yoke 194. This shipper yoke is provided with a suitable hydraulic operating means, as will later be described. The shaft 188 is connected by a clutch 195 to an aligned tubular shaft 196, similarly suitably journaled within the truck frame. Extending centrally through the aligned tubular shafts 188, 196 is a transmission shaft 197 suitably journaled within the truck frame, and splined to the forward end of this shaft is a clutch member 198 having clutch 75

teeth 199 connectible to clutch teeth 200 formed on the forward end of the tubular shaft 196. This clutch member 198 is also provided with clutch teeth 201 engageable with clutch teeth 202 formed on a rotatable member 203. There is provided between the shaft 196 and the rotatable member 203 a substantial speed reduction, and the speed reduction mechanism is herein of the "heliocentric" or continuous-wedge type, similar to that described above in regard to the rotating means for the revolving "cutter head" support 4. The tubular shaft 196 is provided with an eccentric portion 204 on which is rotatably mounted as by roller bearings a drive ring 205. Secured, as by bolts 206, to an annular frame 207 secured within the truck frame, is a guide ring 208 having a series of radially located chambers 209, in each of which is guided a reciprocable plunger 210. The drive ring 205 engages in sliding abutting relationship the inner ends of the plungers, and the outer ends of these plungers are provided with tooth-shaped portions engageable with teeth 211 formed on the rotatable member 203. It will thus be seen that when the shaft 196 is rotated, the rotating member 203 is driven thereby at a substantially reduced speed.

Keyed to the rear end of the shaft 197 is a bevel gear 212 meshing with a bevel gear 213 keyed to a horizontal shaft 214 extending transversely of and suitably journaled within the truck frame. Keyed to and driven by this shaft is a chain sprocket 215 connected by an endless chain 216 to a chain sprocket 217 keyed to the rear truck wheel axle. The front and rear truck wheel axles are connected in driving relation by a chain and sprocket connection 218. There is provided a truck wheel brake comprising a brake drum 219 keyed to the forward end of the transmission shaft 197 of the truck propelling mechanism, and cooperating with this drum is a usual contractible brake band 220 having suitable operating connections 221 (see Fig. 1) having an operating lever 222 conveniently arranged at one side of the truck frame. Adjacent the control lever 222 is a control lever 223 connected through suitable operating connections 224 to a clutch shipper yoke 225 for the clutch member 198. From the foregoing, it will be evident that when the clutch teeth 199 are connected to the clutch teeth 200 and the drive shaft 196 is connected to the transmission shaft 197, the latter may be driven directly from the shaft 196 at a relatively high speed, thereby to effect propulsion of the apparatus along the mine trackway at a relatively high transport speed. When the clutch teeth 201 are connected to the clutch teeth 202, the transmission shaft 197 may be driven from the shaft 196 at a relatively low speed through the "heliocentric" reduction mechanism 139, 145, 146, thereby to propel the apparatus at a relatively low speed suitable for cutting. By applying one or the other of the disc clutches 191, 192, the truck wheels may be driven in either of opposite directions at either a high or a low speed.

Now referring to the various hydraulic control devices, as shown most clearly in Fig. 19, it will be noted that for operating the disc clutches 191, 192 there is provided a cylinder 230 having reciprocable therein a piston 231 having a piston rod 232 pivotally connected at 233 to the clutch shipper yoke 194. Coiled shipper return springs 235, 235 are provided for normally maintaining the shipper yoke in its central or neutral position. It will be evident that when liquid under pressure is supplied to one side or the other of the op-

erating piston 231, the shipper yoke may be swung to apply either the clutch 191 or the clutch 192.

As shown most clearly in Fig. 3, there is secured to the top plate 175 of the turntable casting a vertical cylinder member 236 having reciprocable therein a piston 237 secured to a vertically reciprocable plunger 238. This plunger is provided with a recess 239 for receiving a suitable jack bar, so that when hydraulic pressure is supplied beneath the jack piston 237 the jack bar may be moved into engagement with the mine roof for jacking the apparatus in position on the mine trackway, thereby to hold the apparatus steady during the swinging operation of the kerf cutter.

Liquid under pressure is adapted to be supplied to the cylinders of the turntable rotating, arm swinging, and clutch and jack operating devices, from a gear pump 240 of a well known commercial design, driven by a spur gear 241 keyed to the transmission shaft 58 and meshing with

the pump driving gear connected to one of the pump rotors. As shown in Fig. 3, this pump 240 is arranged within a chamber 243 formed in the turntable casting, and this chamber herein forms a reservoir for the liquid for the hydraulic system. This pump is adapted to pump liquid under relatively high pressure through suitable conduits to the various hydraulic devices under the control of a master control valve 244 of a well known type, while similar control valves 245, 246, 247

and 248 are provided for controlling the liquid supplied under the control of the master valve 244 to the various hydraulic cylinders and the discharge from the latter. These supply and discharge control valves are arranged within valve boxes secured to one side of the swingable turntable frame, as shown in Fig. 1, and are each provided with a suitable control handle; these valves being conveniently located so that as the operator stands beside the mining apparatus dur-

ing the cutting operation the valve handles are within his easy reach. Control valves 249, 250 and 251, similar to the control valves 248, 246 and 244, are provided at the rear of the turntable so that the operator while riding on the rear end of the truck during transport about the mine may control turntable rotation, arm swing, and truck drive.

Referring again to Fig. 19, it will be noted that the master control valve 244 is connected by 50 a conduit 252 to the reservoir 243, and liquid is adapted to be supplied through this conduit, past the master control valve 244, to a conduit 253 leading to the intake of the pump 240. The discharge side of this pump is connected through 55 a conduit 254 to the bottom of the master valve 244 and is adapted to flow under the control of the master valve, through a conduit 255, to the valve chambers at the lower ends of the control valves 245, 246, 247 and 248. The return 60 pipes of the various hydraulic control devices are connected through a conduit 256 to the reservoir 243. The chamber for the valve 245 is connected by a conduit 257 to the lower end of the piston 237 of the jack cylinder 236, while the valve chamber for the valve 246 is connected, through a flexible conduit 258, to the forward end of the clutch operating cylinder 230, and through a flexible conduit 259 to the rear end of the clutch operating cylinder. The chamber for 65 the valve 247 is connected, through a flexible conduit 260, to a conduit 261 connected to the upper ends of the arm swing cylinders 151, and through a flexible conduit 262 to a conduit 263 connected to the lower ends of the arm swing

75

cylinders. The chamber for the valve 248 is connected through a conduit 264 to a flexible conduit 265 communicating with a conduit 266 connected to the opposite ends respectively of the turntable swing cylinders 158, 159, and through a flexible conduit 267 to a conduit 268 connected to the other ends of the turntable swing cylinders. The chamber for the control valve 249 is connected by a conduit 269 to the conduit 267, and through 10 a conduit 270 to the conduit 265. The chamber for the valve 250 is connected through a conduit 271 to the conduit 258, and through a conduit 272 to the conduit 259. The chamber for the valve 251 is connected through a conduit 273, to a conduit 274 also communicating with this valve chamber and the latter conduit is connected to the conduit 256, while liquid under pressure is supplied to the lower ends of the valve chambers through a conduit 275 communicating with the 20 supply conduit 255.

When the master valve 244 is in the open position shown, liquid under pressure may be supplied to the inlet of the pump 240 through conduit 252, past the valve 244, and through the conduit 253; while liquid under pressure may be conducted from the discharge side of the pump through conduit 254, past the valve 244, and through conduit 255 to the valve chambers at the lower ends of the valves 245, 246, 247 and 248. When these valves are in the position shown, liquid under pressure flows past the valve 245 through conduit 257 to effect operation of the jack piston 237 and liquid under pressure also flows past the valve 246, through conduit 259 to one side of the clutch operating piston 231, the other side of the clutch operating piston at this time being connected to the reservoir through conduits 258 and 256. Liquid under pressure also flows past the valve 248 through conduits 264, 265 and 266 to the turntable swing cylinders, the discharge from these cylinders being connected through conduits 268, 267 and 256 to the reservoir. At this time the valve 251 is open, so that liquid under pressure by-passes through conduits 275, 274 and 256. When the valves 245, 246, 247 and 248 are turned into reverse position, the hydraulic devices are operated in the reverse direction. These valves also may of course be rotated into closed position, thereby to cut off 50 all liquid flow to the various hydraulic devices. When the valves 245, 246, 247 and 248 are closed and it is desired to control the turntable rotation and truck drive from the rear end of the truck, the liquid discharge from the valve 251 may be closed and the valves 249 and 250 operated to supply liquid under pressure to the turntable rotation cylinders and clutch operating cylinder.

The general mode of operation of the improved mining apparatus is as follows. The mining apparatus may be propelled along the mine trackway in either of opposite directions at a relatively high transport speed through the transmission mechanism driven by the motor 47 and including the transmission shaft 51, gearing 185, 190 and 186, 187 of the reversing mechanism under the control of the disc clutches 191 and 192, shaft 196, clutch 198, transmission shaft 197, bevel gearing 212, 213, shaft 214 and the chain and sprocket connections 215, 216, 217, 218.

During transport of the mining apparatus about the mine, the arm structure 3, revolving "cutter head" support 4, and kerf cutter 15 are disposed in the position indicated in full lines in

Fig. 2, and during transport the operator is seated on the rear left-hand side of the truck frame, at the rear of the electrical control apparatus 48. The control valves 249, 250 and 251 are located within easy reach of the operator, so that the valve 249 controlling turntable swing and the valve 250 controlling the disc clutches 191 and 192 may be adjusted as desired, it being necessary at times to swing the turntable, together with the arm structure, back and forth with respect to the truck to enable the apparatus to pass around curves in the mine passages. When the working face is reached, the high speed truck wheel drive is disconnected from the motor by releasing the disc clutch and the clutch 198. 15

If it is desired to make a horizontal cut at or near the level of the mine floor, outside and below the level of the mine trackway and in advance of the trackway, in accordance with the well known arcweld method, the operator releases 20 the rotatable kerf cutter locking pin 88, thereby freeing the kerf cutter so that the latter may be swung from the full-line position shown in Fig. 2 to the full-line position shown in Fig. 1, where-in the kerf cutter extends forwardly lengthwise 25 of the arm structure with respect to its pivot. The kerf cutter is then locked in position by the locking pin 88. The operator then applies one or the other of the disc clutches 107, 108 and shifts the clutch member 116 to connect the gear 136 30 to the transmission shaft 105 so that the revolving support 4 may be rotated in one direction or the other about its axis with respect to the arm structure until the kerf cutter assumes a horizontal position beneath the support. The 35 clutches 107, 108 are then released. Liquid under pressure is then supplied to the turntable swing cylinders 158, 159 under the control of the valve 248, thereby causing the turntable, together with the cutting mechanism supported thereby, to be 40 swung horizontally from the central full-line position shown in Fig. 1 to a position wherein the pivot of the kerf cutter lies outside the trackway. The kerf cutter locking pin 88 may be released and connected to different notches 86 so that any 45 desired angular position of the kerf cutter about its pivot may be obtained. The clutch member 116 is shifted to connect the gear 118 to the transmission shaft 105, and upon application of one of the clutches 108, 109 the swingable cutter 50 support 5 is swung about its pivot 13 with respect to the arm structure by the screw, nut and link mechanism 125, 126 and 129. As the cutter support is swung about its pivot, the arm structure is simultaneously swung downwardly about its 55 pivot 12 by the hydraulic cylinder and piston mechanism 151, 152 under the control of the valve 247, the arm structure and cutter support swinging simultaneously about their pivots in opposite directions until the parts assume the lower 60 bottom cutting position indicated in dotted lines in Fig. 2, with the kerf cutter near the level of the mine floor.

When the tip end of the kerf cutter lies adjacent the coal face at the right-hand rib, the operator shifts the clutch 66 to connect the transmission shaft 65 to the shaft 63, thereby to connect the cutter chain 80 of the kerf cutter to its drive, thereby to cause the cutter chain to circulate rapidly about the margin of the cutter 70 bar. The turntable swing control valve 248 is then closed, thereby to lock hydraulically the pistons within the cylinders to hold the turntable against rotative movement with respect to the truck. The operator then shifts the clutch 75

198 into a position to connect the rotatable member 203 to the shaft 197, thereby effecting truck wheel drive through the heliocentric speed reduction mechanism 205, 209, 210, so that the apparatus is propelled at a relatively low speed suitable for cutting, to effect sumping of the kerf cutter beneath the coal face. Upon completion of the sumping cut, the clutch 198 is released and the truck wheel brake 219, 220 set to hold the truck wheels stationary.

The turntable swing control valve 248 is then operated to supply liquid under pressure to the swing cylinders 158, 159, thereby to effect swinging of the turntable and adjustable arm structure about the axis of the turntable laterally from right to left, thereby to swing the kerf cutter from a point adjacent the right-hand rib laterally across the coal face to a point adjacent the left-hand rib; the valve 248 thereafter being adjusted to lock the turntable against rotation. The brake 219, 220 is then released, the clutch 198 connected to the rotatable member 203, and the truck wheels are driven at a relatively low speed suitable for cutting, to propel the apparatus rearwardly along the mine trackway to effect withdrawal of the kerf cutter from beneath the coal.

A horizontal kerf may be cut at or near the level of the mine roof by applying one or the other of the disc clutches 107, 108 and shifting the clutch member 116 to connect the gear 136 to the transmission shaft 105, thereby to effect rotation of the revolving "cutter head" 4 to swing the kerf cutter about the support axis from the bottom cutting position shown in Fig. 2 to the top cutting position indicated in dotted lines in that figure. The arm structure and cutter support are swung about their respective pivots to adjust the kerf cutter into the upper dotted-line position shown in Fig. 2. The kerf cutter is then swung to a position adjacent the right-hand rib, sumped in, swung transversely across the face, and thereafter withdrawn from the coal, in accordance with the usual arcwall method of cutting.

It will be noted that during any of the horizontal cutting positions above described,—for instance when it is desired to cut on a rolling or uneven floor, the kerf cutter may be tilted about transverse and longitudinal axes, i. e. the axes 12 and 13 and the axis of the revolving support 4, to change its angle in altitude. For instance, if it is desired to tilt the tip end of the kerf cutter upwardly or downwardly, this may be accomplished by swinging the cutter support 5 about its pivotal axis 13 with respect to the revolving support; while if it is desired to tip the kerf cutter edgewise, the revolving support may be rotated about its axis.

A shear or vertical cut may be inserted in the coal face by applying one or the other of the disc clutches 107, 108 and shifting the clutch member 116 to connect the gear 136 to the transmission shaft 105, thereby to effect rotation of the revolving support 4 with respect to the arm structure to bring the kerf cutter into a position to swing vertically. The kerf cutter is swung upwardly in a vertical plane by swinging the arm structure 3 about its pivot 12 under the control of the hydraulic cylinders 151 until the tip end of the kerf cutter assumes a position adjacent the mine roof. The apparatus is then propelled forwardly along the trackway at a slow speed to sump the kerf cutter within the coal. Thereafter, the arm structure 3 is swung

downwardly about its pivot 12 to effect swinging of the kerf cutter about the pivot 12 to effect its swinging cut, the kerf cutter swinging downwardly until its tip end reaches the mine floor. The kerf cutter is then withdrawn from the coal by movement of the apparatus rearwardly along the trackway at a low speed.

It will further be noted that by rotating the turntable and simultaneously swinging the cutter support about its pivot 13 the kerf cutter may be positioned to cut vertical kerfs at any desired location between the center of the entry and either rib, one shearing position being indicated in dotted lines in Fig. 1. When the parts are in the dotted-line position shown in Fig. 1, with the kerf cutter arranged at one side of the center of the entry, the arm structure may be swung upwardly to position the tip end of the kerf cutter at the roof, and the apparatus may then be propelled bodily along the trackway to effect sumping of the kerf cutter within the coal face. After the completion of the sumping cut, the arm structure may be swung downwardly to move the kerf cutter in an arcuate path about the arm structure axis 12 to cut an upright, slightly curved kerf in the coal face from a point adjacent the mine roof to a point at the mine floor. Thereafter, the kerf cutter may be moved rearwardly to effect its withdrawal cut by propulsion of the apparatus bodily rearwardly along the trackway. By swinging the cutter support 5 about its vertical pivot 13 from the dotted-line position shown in Fig. 1 to an angularly disposed position, with the tip end of the kerf cutter adjacent the left-hand rib, a similar, upright, slightly curved kerf may be cut in the rib. By swinging the arm structure laterally to the opposite side of the apparatus, a similar cut may be inserted in the opposite rib.

It will further be noted that by rotating the revolving support 4 the kerf cutter may be moved through an arc of a circle to shearing positions at either side of the support axis, this being necessary when vertical kerfs are cut at opposite ribs. During any of the cutting operations above described, the truck is maintained in position on the trackway during swinging movement of the kerf cutter, by the hydraulic, roof engaging jack mechanism 237, 238 controlled by the valve 245.

As a result of this invention it will be noted that an improved coal mining apparatus is provided, having improved adjustable kerf cutting mechanism whereby horizontal kerfs may be cut at or near the level of the mine floor, either in front or outside and below the level of the mine trackway, horizontal kerfs at any desired location between the mine roof and mine floor, and vertical kerfs at any desired location between the ribs of the entry. It will further be noted that by the provision of the improved adjustable supporting mechanism for the kerf cutting mechanism, the kerf cutter may not only be positioned at any desired location between the mine roof and mine floor and ribs of the entry, but may also be tilted about longitudinal and transverse axes to change its angle in altitude, thereby to accommodate itself to a rolling or uneven floor or pitching coal seam. It will still further be noted that an improved coal mining apparatus is provided wherein the adjusting mechanism for the kerf cutter is extremely flexible and has a wide range of adjustment, it being possible to locate the kerf cutter to cut kerfs in the coal face and ribs to suit any mining condition encountered. These and other uses and advantages of the im-

proved mining apparatus will be clearly apparent to those skilled in the art.

While there is in this application specifically described one form which the invention may assume in practice, and several methods of use thereof, it will be understood that the same are shown for purposes of illustration and that the invention may be modified and embodied in various other forms without departing from its spirit or the scope of the appended claims.

What I claim as new and desire to secure by Letters Patent is:

1. In a mining apparatus, a portable base, an arm structure pivotally mounted on said base to swing in a vertical direction relative thereto, a cutter support swingably mounted on the outer extremity of said arm structure, a kerf cutter pivotally mounted on said cutter support to swing relative thereto, a motor on said base relative to which said arm structure is swingable, devices driven by said motor for actuating said kerf cutter including a transmission shaft extending longitudinally of said arm structure, and devices driven by said shaft for swinging said cutter support relative to said arm structure including a screw and nut mechanism parallel with said shaft.
2. In a mining apparatus, a portable base, an arm structure pivotally mounted on said base to swing in a vertical direction relative thereto, a cutter support swingably mounted on the outer extremity of said arm structure, a kerf cutter pivotally mounted on said cutter support to swing relative thereto, a motor on said base relative to which said arm structure is swingable, devices driven by said motor for actuating said kerf cutter including a transmission shaft extending longitudinally of said arm structure, and devices driven by said shaft for swinging said cutter support relative to said arm structure including a screw and nut mechanism including a guideway on said arm structure, a screw extending longitudinally of said guideway in parallelism with said shaft, a nut engaging said screw and guided in said guideway, and a link connecting said nut to said cutter support.
3. In a mining apparatus, a portable base, an arm structure pivotally mounted on said base to swing in a vertical direction relative thereto, a cutter support swingably mounted on the outer extremity of said arm structure, a kerf cutter pivotally mounted on said cutter support to swing relative thereto, a motor on said base relative to which said arm structure is swingable, devices driven by said motor for actuating said kerf cutter including a transmission shaft extending longitudinally of said arm structure, and devices driven by said shaft for swinging said cutter support relative to said arm structure including a screw and nut mechanism including a guideway on said arm structure, a screw extending longitudinally of said guideway in parallelism with said shaft, a nut engaging said screw and guided in said guideway and a link connecting said nut to said cutter support, and mechanism for rotating said screw in either of opposite directions.
4. In a mining apparatus, a portable base, an arm structure pivotally mounted on said base to swing in a vertical direction relative thereto, a revolving support mounted on said arm structure to rotate relative thereto about an axis extending longitudinally of said arm structure, a cutter support swingably mounted on said revolving sup-

port, a kerf cutter mounted on said cutter support to swing relative thereto, motor operated mechanism for actuating said kerf cutter including a transmission shaft extending longitudinally of said arm structure, and mechanism driven by said transmission shaft and carried by said revolving support for swinging said cutter support relative thereto including a screw and nut mechanism parallel with said shaft, the screw of the latter mounted on said revolving support and arranged with its axis parallel with the axis of said revolving support and rotatable with the latter about the support axis.

5. In a mining apparatus, a portable base, an arm structure pivotally mounted on said base to swing in a vertical direction relative thereto, a revolving support mounted on said arm structure to rotate relative thereto about an axis extending longitudinally of said arm structure, a cutter support swingably mounted on said revolving support, a kerf cutter mounted on said cutter support to swing relative thereto, motor operated mechanism for actuating said kerf cutter including a transmission shaft extending longitudinally of said arm structure, and mechanism driven by said transmission shaft and carried by said revolving support for swinging said cutter support relative thereto including a screw and nut mechanism, said screw and nut mechanism including a guideway extending longitudinally of said revolving support, a screw extending longitudinally of said guideway in parallelism with said shaft, a nut engaging said screw and guided in said guideway and a link connecting said nut with said cutter support.

6. In a mining apparatus, a portable base, kerf cutting mechanism mounted on said base for swinging movement relative thereto, and mechanism for swinging said kerf cutting mechanism selectively in opposite directions relative to said base including a pair of hydraulic cylinder and piston devices on the base for swinging said kerf cutting mechanism and relative to which devices said kerf cutting mechanism is swingable when swung by them, one device extensible to swing said cutting mechanism in one direction and the other device extensible to swing said cutting mechanism in the opposite direction, and a speed multiplying mechanism operatively connected to the pistons of said devices and said cutting mechanism, the latter being swung in opposite directions by said hydraulic devices through said speed multiplying mechanism, said speed multiplying mechanism including a member fixed to said base, a member fixed to said cutting mechanism, and a cooperating rotatable member engaging said members and to which said devices are operatively connected.

7. In a mining apparatus, a portable base, kerf cutting mechanism mounted on said base for swinging movement relative thereto and mechanism for swinging said kerf cutting mechanism selectively in opposite directions relative to said base including a pair of hydraulic cylinder and piston devices on said base, one device extensible to swing said cutting mechanism in one direction and the other device extensible to swing said cutting mechanism in the opposite direction, and an intermeshing rack and gear speed multiplying mechanism operatively connected to said pistons and said cutting mechanism, the latter being swung in opposite directions by said devices through said speed multiplying mechanism, said speed multiplying mechanism includ-

ing a rack fixed to said base, a rack fixed to said cutting mechanism, and a gear meshing with said racks and operatively connected to said devices for actuation by the latter.

5. 8. In a mining apparatus, a portable base, kerf cutting mechanism, and mechanism for swinging said kerf cutting mechanism relative to said base including a pair of hydraulic cylinder and piston devices on the base, intermeshing rack and gear 10 connections between the pistons thereof and said cutting mechanism, said connections including an arcuate guide to which the piston rods are pivotally connected, a stationary arcuate rack secured to the base, a movable arcuate rack 15 movable with the cutting mechanism, and a gear carried by said guide and meshing with said racks.

9. In a mining apparatus, a portable base, a motor thereon, a horizontal turntable on said 20 base rotatable relative thereto and to said motor, said turntable having an arm portion overlying the forward end of the base and a depending frame portion projecting downwardly from the outer extremity of said arm portion, an arm 25 structure pivotally mounted on said arm portion to swing in a vertical direction relative thereto, connections between the lower end of the depending frame portion and said arm for swinging said arm relative to said turntable, a revolving 30 support mounted on said arm structure to rotate relative thereto about an axis extending longitudinally of the arm structure, gearing actuated by power from said motor and carried by said arm structure for revolving said support relative 35 to said arm structure, a cutter support swingably mounted on the outer extremity of said revolving support, and a kerf cutter mounted on said swingable support to swing relative thereto.

10. In a mining apparatus, a portable base, a 40 motor thereon, a horizontal turntable on said base rotatable relative to the latter and to said motor, said turntable having an arm portion overlying the forward end of the base and a depending frame portion projecting downwardly from the outer extremity of said arm portion, an arm 45 structure pivotally mounted on said arm portion to swing in a vertical direction relative thereto, connections between the lower end of the depending frame portion and said arm for swinging said arm relative to said turntable, a revolving 50 support mounted on said arm structure to rotate relative thereto about an axis extending longitudinally of the arm structure, gearing actuated by power from said motor and carried by said arm structure for revolving said support relative 55 to said arm structure, a cutter support swingably mounted on the outer extremity of said revolving support, mechanism carried by said revolving support for swinging said cutter support relative thereto, and a kerf cutter mounted on said swingable support to swing relative thereto.

11. In a mining apparatus, a portable base, a horizontal turntable on said base, said turntable 60 having an arm portion overlying the forward end of the base and a depending frame portion projecting downwardly from the outer extremity of said arm portion, an arm structure pivotally mounted on said arm portion to swing in a vertical direction relative thereto, connections between the lower end of the depending frame portion and said arm for swinging said arm relative to said turntable, a revolving support 65 mounted on said arm structure to rotate relative thereto about an axis extending longitudi-

nally of the arm structure, gearing carried by said arm structure for revolving said support relative to said arm structure, a cutter support swingably mounted on the outer extremity of said revolving support, mechanism carried by 5 said revolving support for swinging said cutter support relative thereto, and a kerf cutter mounted on said swingable support to swing relative thereto, said rotating means for said revolving support including a heliocentric speed reducing 10 mechanism between said arm structure and said revolving support and said cutter support swinging means including a screw and nut mechanism carried by said revolving support.

12. In a mining apparatus, a portable base, a support on said base, a cutter support pivotally mounted on said support to swing relative thereto about an axis at right angles to the longitudinal axis of said first support, a kerf cutter carried by said cutter support, motor operated 20 means for actuating said kerf cutter including a transmission shaft arranged with its axis extending longitudinally of said first support at right angles to the axis of swinging movement of said cutter support, and means driven by said 25 shaft for swinging said cutter support with respect to said first support including a shaft coaxial with and rotatable relative to said transmission shaft during swinging of said cutter support, and operative connections between said coaxial shaft and said cutter support.

13. In a mining apparatus, a portable base, a support mounted on said base for rotation with respect thereto about its longitudinal axis, a cutter support pivotally mounted on said rotatable 35 support to swing relative thereto about an axis at right angles to the longitudinal axis of said rotatable support, a kerf cutter carried by said cutter support, motor operated means for actuating said kerf cutter including a transmission 40 shaft arranged with its axis extending longitudinally of and aligned with the axis of rotation of said rotatable support, and means driven by said shaft for swinging said cutter support about its pivot with respect to said rotatable support including a shaft coaxial with and rotatable relative to said transmission shaft during swinging of said cutter support, and operative connections between said coaxial shaft and said cutter support.

14. In a mining apparatus, a portable base, an arm pivotally mounted on said base to swing relative thereto, a support mounted on said arm for rotation with respect thereto about a longitudinal axis extending at right angles to the 55 arm pivot axis, a cutter support pivotally mounted on said rotatable support to swing relative thereto about an axis at right angles to the axis of rotation of said rotatable support, a kerf cutter carried by said cutter support, motor operated means for actuating said kerf cutter including a transmission element journaled in said arm, a transmission element driven by said transmission element and arranged with its axis coincident with the axis of rotation of said rotatable support, and means driven by said last mentioned transmission element for swinging said cutter support with respect to said rotatable support including a transmission element coaxial with and rotatable relative to said first mentioned transmission element during swinging of said cutter support, and operative connections between said coaxial transmission element and said cutter support.

15. In a mining apparatus, a support, a cutter 75

support pivotally mounted on said support to swing relative thereto about an axis at right angles to the longitudinal axis of said first support, a kerf cutter carried by said cutter support, 5 motor operated means for actuating said kerf cutter including a transmission shaft arranged with its axis coincident with the longitudinal axis of said first support within the latter, and means driven by said transmission shaft for 10 swinging said cutter support relative to said first support and including a shaft coaxial with and rotatable relative to said transmission shaft during swinging of said cutter support, and operative connections between said coaxial shaft and 15 said cutter support.

16. In a mining apparatus, a support, a cutter support pivotally mounted on said support to swing relative thereto about an axis at right angles to the longitudinal axis of said support, a 20 plane kerf cutter carried by said cutter support, said cutter support pivot axis arranged parallel with the plane of said kerf cutter, motor operated means for actuating said kerf cutter including a transmission shaft arranged with its axis coincident with the longitudinal axis of said first support, and means driven by said shaft for 25 swinging said cutter support about its pivotal axis relative to said first support to move said kerf cutter into relatively inclined cutting planes 30 including relatively rotatable threadedly engaged screw and nut elements arranged with their axes parallel with the longitudinal axis of said first support and mounted on the latter, means driven by said shaft for effecting relative rotation between 35 said screw and nut elements to effect rectilinear movement of one of said elements, and a connection between said rectilinearly movable element and said cutter support.

17. In a mining apparatus, a support, a cutter support pivotally mounted on said support to swing relative thereto about an axis at right angles to the longitudinal axis of said first support, a plane kerf cutter carried by said cutter support, said cutter support pivot axis arranged 40 parallel with the plane of said kerf cutter, motor operated means for actuating said kerf cutter including a transmission shaft arranged with its axis coincident with the longitudinal axis of said first support, means driven by said transmission shaft for swinging said cutter support about its 45 pivotal axis relative to said first support to move said kerf cutter into relatively inclined cutting planes including a screw arranged with its axis parallel with the longitudinal axis of said first support and journaled on the latter, driving connections between said shaft and said screw, a nut 50 engaging said screw and movable rectilinearly therealong, and a connection between said nut and said cutter support.

18. In a mining apparatus, a portable base, but a single rigid arm pivotally mounted on said base to swing in a vertical direction relative thereto, a cutter support pivotally mounted on said arm to swing relative thereto about an axis 55 at right angles to the longitudinal axis of said arm, a kerf cutter carried by said cutter support, motor operated means for actuating said kerf cutter including a shaft journaled on said arm, and means driven by said shaft for swinging said cutter support relative to said arm and including a shaft parallel with said shaft and likewise journaled on said arm.

19. In a mining apparatus, a portable base, but a single rigid arm pivotally mounted on said base to swing in a vertical direction relative 75

thereto, a support mounted on said arm for rotation with respect thereto about an axis at right angles to the arm pivot axis, a cutter support pivotally mounted on said rotatable support to swing relative thereto about an axis at right angles to the axis of rotation of said first support, a kerf cutter carried by said cutter support, 5 motor operated means for actuating said kerf cutter including a shaft journaled on said arm, means driven by said shaft for rotating said first support relative to said arm, and means driven by said shaft for swinging said cutter support relative to said first support, said rotating and swinging means for said supports including a shaft parallel with said shaft and likewise journaled on said arm. 10 15

20. In a mining apparatus, a portable base, an arm pivotally mounted on said base to swing in a vertical direction relative thereto, a support mounted on said arm for rotation relative thereto about an axis at right angles to the arm pivot axis, a cutter support pivotally mounted on said rotatable support to swing relative thereto about an axis at right angles to the axis of rotation of said rotatable support, a kerf cutter carried by 25 said cutter support, motor operated means for actuating said kerf cutter including shafting journaled in said arm and said rotatable support centrally within the latter, means carried by said arm and driven by said shafting for rotating said first support relative to said arm, and means carried by said first support and driven by said shafting for swinging said cutter support relative to said first support, said cutter support swinging means including cooperating relatively 30 rotatable swinging members having relative rectilinear movement upon relative rotation thereof and means for effecting relative rotation of said members. 35

21. In a mining apparatus, a portable base, a horizontal turntable on said base, cutter adjusting means mounted on said turntable, hydraulic devices for rotating said turntable, for adjusting said cutter adjusting means and for controlling base propulsion, control means for said hydraulic devices located at the forward end of said base at one side of said turntable, and auxiliary control means for controlling said hydraulic turntable rotation device and said base propulsion controlling device and located on said base at the rear of said turntable. 40 45 50

22. In a mining apparatus, kerf cutting mechanism mounted for swinging movement, and swinging mechanism therefor for swinging the cutting mechanism in opposite directions including a pair of hydraulic cylinder and piston devices relative to which, upon actuation by said devices, said cutting mechanism is swingable, one device extensible to swing said cutting mechanism in one direction and the other device extensible to swing said cutting mechanism in the opposite direction, and a speed multiplying means common to both hydraulic devices and operatively connected between said hydraulic devices and said cutting mechanism for swinging the latter a distance substantially greater than the distance of piston travel with respect to the cylinders, said speed multiplying means comprising a member movable about the axis of swing of said cutting mechanism, an actuating member carried thereby, and a member also movable about said axis of swing and actuated by said actuating member. 60 65 70

23. In a mining apparatus, kerf cutting mechanism mounted for swinging movement, and swinging mechanism therefor for swinging the cutting mechanism in the opposite directions in 75

- cluding a pair of hydraulic cylinder and piston devices relative to which, upon actuation by said devices, said cutting mechanism is swingable, one device extensible to swing the cutting mechanism 5 in one direction and the other device extensible to swing the cutting mechanism in the opposite direction, and a speed multiplying means common to both hydraulic devices and operatively connected between said hydraulic devices and 10 said cutting mechanism, said speed multiplying means embodying a movable element to which the pistons of said devices are both connected and an actuating member carried by and rotatable relative to said movable member.
- 15 24. In a mining apparatus, kerf cutting mechanism mounted for swinging movement, and swinging mechanism therefor for swinging the cutting mechanism in the opposite directions including a pair of hydraulic cylinder and piston devices, one device extensible to swing the cutting mechanism in one direction and the other device extensible to swing the cutting mechanism in the opposite direction, a speed multiplying means common to both devices and operatively connected between said hydraulic devices and said cutting mechanism, said speed multiplying means embodying a movable element to which the pistons of said devices are both connected, a relatively stationary element, and connections between said stationary and movable elements including a rotatable actuating member carried by and rotatable relative to said movable element and engaging said stationary element.
- 25 25. In a mining apparatus, kerf cutting mechanism, and swinging mechanism therefor including a pair of hydraulic cylinder and piston devices, intermeshing rack and gear connections between the pistons of said devices and said cutting mechanism, said connections including an arcuate guide to which the pistons are pivotally connected, a stationary arcuate rack, a movable arcuate rack, and a gear carried by said arcuate guide and meshing with said racks.
- 30 26. In a mining apparatus, kerf cutting mechanism, and swinging mechanism therefor including a hydraulic cylinder and piston device, intermeshing rack and gear connections between the piston of said device and said cutting mechanism, said connections including an arcuate guide to which the piston is connected, a stationary arcuate rack, a movable arcuate rack, and a gear carried by said arcuate guide and meshing with said racks.
- 35 27. In a mining apparatus, a portable base, a horizontal turntable on said base, cutter adjusting means mounted on said turntable, devices for rotating said turntable, for adjusting said cutter adjusting means and for controlling base propulsion, control means for said devices located at the forward end of said base at one side of said turntable, and auxiliary control means for controlling said turntable rotation device and said base propulsion controlling device and located on said base at the rear of said turntable.
- 40 28. In a mining apparatus, a portable base, an arm structure pivotally mounted on said base to swing in a vertical direction relative thereto, a cutter head mounted on said arm structure for rotation about an axis extending longitudinally of the arm structure, a kerf cutter carried by said cutter head, mechanism for actuating the kerf cutter including a transmission shaft arranged longitudinally of said arm structure with its axis coincident with the head axis, and means 45 driven by said shaft for rotating said cutter head.
- 45 including a shaft arranged parallel with said transmission shaft and mounted on said arm structure, and speed reducing means operatively connected between said parallel shaft and said cutter head and including cooperating relatively 50 rotatable speed reducing elements arranged with their axes coincident with the head axis.
- 50 29. In a mining apparatus, a portable base, an arm structure pivotally mounted on said base to swing in a vertical direction relative thereto, a cutter head mounted on said arm structure for rotation about an axis extending longitudinally of the arm structure, a kerf cutter carried by said cutter head, means for actuating said kerf cutter including a transmission shaft extending longitudinally of said arm structure with its axis coincident with the head axis, and means driven by said transmission shaft for rotating said head selectively in either of opposite directions including a shaft arranged on said arm structure in parallel relation with said transmission shaft, reversing mechanism between said transmission shaft and said parallel shaft for effecting rotation of said parallel shaft selectively in either of opposite directions while said transmission shaft rotates continuously in the same direction, and speed reducing means operatively connected between said parallel shaft and said cutter head including relatively rotatable speed reducing elements arranged coaxially with said transmission shaft with their axes coincident with the cutter head axis.
- 55 30. In a mining apparatus, a portable base, an arm structure pivotally mounted on said base to swing in a vertical direction relative thereto, a cutter head mounted on said arm structure for rotation about an axis extending longitudinally of the arm structure, a cutter support pivotally mounted on said cutter head to swing relative thereto about an axis at right angles to the head axis, a kerf cutter carried by said cutter support, means for actuating said kerf cutter including a transmission shaft extending longitudinally of said arm structure with its axis coincident with the cutter head axis, and means driven by said transmission shaft for rotating said cutter head and swinging said cutter support about its pivot including a shaft parallel with said transmission shaft, gearing connecting said parallel shaft with said transmission shaft, speed reducing means operatively connecting said parallel shaft with the cutter head, means including a shaft coaxial with said transmission shaft for transmitting swinging movement to said cutter support, and gearing connecting said parallel shaft with said coaxial shaft.
- 60 31. In a mining apparatus, a support, a cutter head rotatably mounted on said support, a cutter support pivotally mounted on said cutter head to swing relative thereto about an axis at right angles to the head axis, a kerf cutter carried by said cutter support, means for actuating said kerf cutter including transmission shafting extending axially along the head axis through the cutter head, a shaft coaxial with said shafting and carried by said first mentioned support, means driven by said shafting including a head rotating element surrounding said coaxial shaft and operatively connected to the cutter head for rotating the latter relative to said first mentioned support, and means driven by said shafting including a driving element secured to said coaxial shaft and cutter support-swinging means actuated by the latter for swinging said cutter support relative to said cutter head.

32. In a mining apparatus, a portable base, a vertically-swingable support on said base, a cutter support pivotally mounted on said support to swing relative thereto about an axis at 5 right angles to the longitudinal axis of said first support, a kerf cutter carried by said cutter support, said cutter support swingable about its pivot relative to said first support to move said kerf cutter into relatively inclined cutting planes, 10 motor operated means for actuating said kerf cutter including a transmission shaft arranged with its axis extending longitudinally of said first support at right angles to the axis of swinging movement of said cutter support, and means 15 including reversing gearing on said vertically swingable support and driven by said shaft for swinging said cutter support in either of opposite directions with respect to said first support without reversing the direction of drive of said 20 kerf cutter.

33. In a mining apparatus, a portable base, a support mounted on said base for rotation with respect thereto about its longitudinal axis, a cutter support pivotally mounted on said rotatable 25 support to swing relative thereto about an axis at right angles to the axis of rotation of said first support, a kerf cutter carried by said cutter support, said cutter support swingable about its pivot relative to said first support to move said 30 kerf cutter into relatively inclined cutting planes, motor operated means for actuating said kerf cutter including a transmission shaft arranged with its axis alined with the axis of rotation of said first support, and means driven by said 35 shaft for swinging said cutter support in either of opposite directions about its pivot with respect to said first support without reversing the direction of drive of said kerf cutter.

34. In a mining apparatus, a vertically-swingable support, a cutter support pivotally mounted 40 on said first support to swing relative thereto about an axis at right angles to the longitudinal axis of said first support, a kerf cutter carried by said cutter support, said cutter support swingable about its pivot relative to said first support to move said kerf cutter into relatively inclined cutting planes, motor operated means for actuating said kerf cutter including a transmission shaft arranged with its axis coincident with the 45 longitudinal axis of said first support within the latter, and means driven by said transmission shaft and including reversing gearing carried by said first support for swinging said cutter support in either of opposite directions relative to 50 said first support without reversing the direction of drive of said kerf cutter.

35. In a mining apparatus, a portable base, an arm pivotally mounted on said base to swing in a vertical direction relative thereto, a cutter support pivotally mounted on the outer extremity of 60 said arm to swing relative thereto, a kerf cutter carried by said cutter support, motor operated means for actuating said kerf cutter including a transmission shaft arranged with its axis extending longitudinally of said arm, and means for swinging said cutter support about its pivot including a shaft parallel with said transmission shaft and journaled on said arm, a shaft coaxial with and rotatable relative to said transmission shaft, driving connections between said transmission shaft and said parallel shaft and between 65 said parallel shaft and said coaxial shaft, and operative swinging connections between said coaxial shaft and said cutter support.

36. In a mining apparatus, a portable base, an arm pivotally mounted on said base to swing in a vertical direction relative thereto, a cutter support pivotally mounted on the outer extremity of 5 said arm to swing relative thereto, a kerf cutter carried by said cutter support, motor operated means for actuating said kerf cutter including a transmission shaft arranged with its axis extending longitudinally of said arm, and means for 10 swinging said cutter support about its pivot including a shaft parallel with said transmission shaft and journaled on said arm, a shaft coaxial with and rotatable relative to said transmission shaft, driving connections between said transmission shaft and said parallel shaft and between 15 said parallel shaft and said coaxial shaft and operative swinging connections between said coaxial shaft and said cutter support including a fourth shaft parallel with said coaxial shaft.

37. In a mining apparatus, a portable base, an arm pivotally mounted on said base to swing in a vertical direction relative thereto, a cutter head mounted on said arm for rotation about an axis alined with the longitudinal axis of said arm, a cutter support pivotally mounted on said cutter 25 head to swing relative thereto about an axis at right angles to the head axis, a kerf cutter carried by said cutter support, motor operated means for actuating said kerf cutter including a transmission shaft arranged with its axis alined with the 30 longitudinal axis of said arm, and means driven by said transmission shaft for rotating said cutter head in either of opposite directions about its axis relative to said arm while said transmission shaft rotates continuously in the same direction including a shaft parallel with said transmission shaft and journaled on said arm, reversing gearing between said transmission shaft and said parallel shaft, and driving gearing between 35 said parallel shaft and said rotatable head, said driving gearing including a gear arranged with its axis alined with the cutter head axis and rotatable relative to said cutter head during head rotation.

38. In a mining apparatus, a swingable support, a cutter head mounted on said swingable support for rotation about an axis extending longitudinally of said swingable support, a cutter support pivotally mounted on said cutter head to swing relative thereto about an axis at right 45 angles to the head axis, a kerf cutter carried by said cutter support, motor operated means for driving said kerf cutter including a transmission shaft arranged with its axis alined with the longitudinal axis of said swingable support, means driven by said shaft for rotating said cutter head including a shaft parallel with said transmission shaft and journaled on said swingable support, driving connections between said transmission shaft and said parallel shaft and between 50 said parallel shaft and said cutter head, and means for swinging said cutter support about its pivot including a shaft coaxial with and rotatable relative to said transmission shaft, driving means between said 55 parallel shaft and said coaxial shaft, and operative connections between said coaxial shaft and said cutter support.

39. In a mining apparatus, a swingable support, a cutter head mounted on said swingable support for rotation about an axis extending longitudinally of said swingable support, a cutter support pivotally mounted on said cutter head to swing relative thereto about an axis at right 60 angles to the head axis, a kerf cutter carried 65

5 by said cutter support, motor operated means for driving said kerf cutter including a transmission shaft arranged with its axis alined with the longitudinal axis of said swingable support, means driven by said shaft for rotating said cutter head including a shaft parallel with said transmission shaft and journaled on said swingable support, driving connections between said transmission shaft and said parallel shaft and driving connections between said parallel shaft and said cutter head, and means for swinging said cutter support about its pivot including a shaft coaxial with and rotatable relative to said transmission shaft, driving means between said parallel shaft and said coaxial shaft, and operative connections between said coaxial shaft and said cutter support, and clutch means for selectively connecting said head rotating connections and said cutter support swinging connections in driving relation with said parallel shaft.

10 40. In a mining apparatus, a swingable support, a cutter head mounted on said swingable support for rotation about an axis extending longitudinally of said swingable support, a cutter support pivotally mounted on said cutter head to swing relative thereto about an axis at right angles to the head axis, a kerf cutter carried by said cutter support, motor operated means for driving said kerf cutter including a transmission shaft arranged with its axis alined with the longitudinal axis of said swingable support, means driven by said shaft for rotating said cutter head including a shaft parallel with said transmission shaft and journaled on said swingable support, driving connections between said transmission shaft and said parallel shaft and driving connections between said parallel shaft and said cutter head, and means for swinging said cutter support about its pivot including a shaft coaxial with and rotatable relative to said transmission shaft, driving means between said parallel shaft and said coaxial shaft, and operative connections between said coaxial shaft and said cutter support, said head rotation and cutter support swinging connections including reversing gearing for effecting head rotation and cutter support swing in either of opposite directions while said transmission shaft rotates continuously in the same direction.

15 45. In a mining apparatus, a portable base, a support on said base, a cutter support pivotally mounted on said first support to swing relative thereto about an axis at right angles to the longitudinal axis of said first support, a kerf cutter carried by said cutter support, motor operated means for actuating said kerf cutter including a transmission shaft arranged with its axis extending longitudinally of said first support at right angles to the axis of swinging movement of said cutter support, and means driven by said shaft for swinging said cutter support in either of opposite directions with respect to said first support including a shaft coaxial with and rotatable relative to said transmission shaft, a reversing mechanism between said transmission shaft and said coaxial shaft for rotating the latter selectively in opposite directions while said transmission shaft rotates always in the same direction, and operative connections between said coaxial shaft and said cutter support.

20 46. In a mining apparatus, a support, a cutter support pivotally mounted on said support to swing relative thereto about an axis at right angles to the longitudinal axis of said first support, a kerf cutter carried by said cutter support, motor operated means for driving said kerf cutter including a transmission shaft arranged with its axis alined with the longitudinal axis of said first support, means

driven by said shaft for rotating said cutter head including a shaft parallel with said transmission shaft and journaled on said first support, driving connections between said transmission shaft and said parallel shaft and driving connections between said parallel shaft and said cutter head, and means for swinging said cutter support about its pivot relative to said cutter head including a shaft coaxial with and rotatable relative to said transmission shaft, driving connections between said parallel shaft and said coaxial shaft and operative connections between said coaxial shaft and said cutter support.

47. In a mining apparatus, a support, a cutter head mounted on said support for rotation about an axis extending longitudinally of said support, a cutter support pivotally mounted on said cutter head to swing relative thereto about an axis at right angles to the head axis, a kerf cutter carried by said cutter support, motor operated means for driving said kerf cutter including a transmission shaft arranged with its axis alined with the longitudinal axis of said first support, means for rotating said cutter head including a shaft parallel with said transmission shaft and journaled on said first support, driving connections between said transmission shaft and said parallel shaft and driving connections between said parallel shaft and said cutter head, and means for swinging said cutter support about its pivot relative to said cutter head including a shaft coaxial with and rotatable relative to said transmission shaft, driving connections between said parallel shaft and said coaxial shaft and operative connections between said coaxial

shaft and said cutter support, and clutch means for selectively connecting said head rotating connections and said cutter support swinging connections in driving relation with said parallel shaft. 5

48. In a mining apparatus, a support, a cutter head mounted on said support for rotation about an axis extending longitudinally of said support, a cutter support pivotally mounted on said cutter head to swing relative thereto about an axis at 10 right angles to the head axis, a kerf cutter carried by said cutter support, motor operated means for driving said kerf cutter including a transmission shaft arranged with its axis alined with the longitudinal axis of said first support, means for rotating said cutter head including a shaft parallel with said transmission shaft and journaled on said first support, driving connections between said transmission shaft and said parallel shaft and driving connections between said parallel shaft and said cutter head, and means for swinging said cutter support about its pivot relative to said cutter head including a shaft coaxial with and rotatable relative to said transmission shaft, driving connections between said parallel shaft and said coaxial shaft and operative connections between said coaxial shaft and said cutter support, said head rotation and cutter support swinging connections including reversing gearing for effecting head rotation and cutter support swing in either of opposite directions while said transmission shaft rotates continuously in the same direction. 20 25 30

DWIGHT R. RICHARDS. 35

CERTIFICATE OF CORRECTION.

Patent No. 2,099,373.

November 16, 1937.

DWIGHT R. RICHARDS.

It is hereby certified that error appears in the printed specification of the above numbered patent requiring correction as follows: Page 9, first column, line 58, claim 10, after the word "mechanism" insert actuated by power from said motor and; page 12, second column, line 66, claim 38, strike out the comma after "shaft" second occurrence; and that the said Letters Patent should be read with these corrections therein that the same may conform to the record of the case in the Patent Office.

Signed and sealed this 25th day of January, A. D. 1938.

Henry Van Arsdale,

Acting Commissioner of Patents.
